UNITED STATES PATENT OFFICE.

SAMUEL W. FORNEY, OF PULASKI, VIRGINIA.

MUFFLER.

1,027,469.

Specification of Letters Patent. Patented May 28, 1912.

Application filed August 29, 1911. Serial No. 646,576.

To all whom it may concern:

Be it known that I, SAMUEL W. FORNEY, a citizen of the United States, residing at Pulaski, in the county of Pulaski and State 5 of Virginia, have invented certain new and useful Improvements in Mufflers, of which the following is a specification.

My invention relates to improvements in automobile mufflers, and has for its leading 10 object the provision of an improved muffler which will reduce to a minimum the back pressure and the noxious smell and smoke of the gases and consequently will but slightly retard or impede the operation of 15 the engine but which will thoroughly and satisfactorily break up the compact gases discharged from the cylinders to cause said gases to empty into the outer air with practically no sound, smell or smoke.

20 The further object of my invention is the provision of an improved muffler for automobiles which will serve to deaden the noise of the explosion and eliminate smell and smoke by mixing with the exhaust gases 25 and which will regulate the quantity of air according to the speed at which the automobile is traveling and will consequently be of equal efficiency and have but slight back pressure at all times irrespective of the 30 speed of the explosions.

Other objects and advantages of my improved muffler will be readily apparent by reference to the following description taken in connection with the accompanying drawings, 35 and it will be understood that I may make any modifications in the specific structure shown and described within the scope of my claims without departing from or exceeding the spirit of my invention.

40 Figure 1 represents a view of my complete muffler. Fig. 2 represents a view thereof with the inclosing casing shown in section. Fig. 3 represents a longitudinal sectional view of the entire muffler. Fig. 45 4 represents a cross sectional view thereof on the line 4—4 of Fig. 1, and Fig. 5 represents a sectional view on the line 5—5 of said figure.

In the drawings, the numeral 1 designates 50 the main casing of my improved muffler, said casing having the flaring front bell portion 2 and having at its other end the tapering neck 3 terminating in the exhaust pipe 4.

55 Leading toward and projecting within the casing 1 is the exhaust pipe 5 which has

mounted thereon a collar 6 bearing the radiating arms 7 which are secured to and serve to support the rear end of the pipe 8. Said pipe flares rearwardly and terminates in 60 the bell portion 9 which extends outward and is secured to the interior of the casing 1. Said bell portion and the tapering end of the casing together inclose the mixing chamber 10 having extending thereacross the 65 brace 11 bearing the conoid deflector 12 for aiding in breaking up the exhaust gases, a screen 13 being secured at the termination of the main portion of the casing and serving to further break up the exhaust gases, 70 and to cause a thorough mixing of said gases with the air in the chamber 10.

Radiating from the pipe 8 are the small 75 forwardly inclined air receiving branch pipes 14, while inclosing the pipe 8 and branches 14 is a branch or supplemental casing 15 having ports through which the pipes 14 communicate with the space inclosed by the casing 1.

In the use of my muffler as the automobile equipped therewith moves forward air will be caught by the bell 2 of the casing 1 and continued movement of the machine will cause said air to pass through the pipes 14 into the flaring exhaust pipe 8. To further supplement passage of air into the pipe 8 I connect the ends of the pipes 8 and 15 by the partition or wall 16 which is so flared as to guide air into the pipe 8. The flaring of the pipe 8 allows the air and exhaust 90 gases to mix without causing a back pressure in the exhaust pipes while the rush of air in at the rear end of the pipe 8 and also in through the various pipes 14 eliminates all danger of back pressure, this gas increasing with the speed of the machine and consequently driving out the exhaust gases at approximately the same proportional speed relative to the speed of operation of the engine.

100 The exhaust air and gases, and the air rushing into the pipe 8 or drawn thereinto by the force of the exhaust are further mixed by striking against the deflector 12 and screen 13 before passing out of the chamber 10 and discharge pipe 4.

105 From the foregoing description taken in connection with the accompanying drawings the construction and operation of my improved muffler for automobiles will be readily understood, and it will be seen that I have provided a simple and efficient 110

muffler which while but slightly retarding the outward flow of the exhaust gases and thus but little hampering the efficiency of the engine will satisfactorily break up the body of said gases and mix the same with air before they are allowed to pass from the muffler and will thus satisfactorily muffle the engine, and eliminate the smell and smoke delivered from the exhaust.

10 I claim:

1. An automobile muffler comprising an outer casing having a flanged end, a pipe mounted in said casing and inclosed in a second casing, said casing and pipe being provided with perforations, branch pipes having their inner ends secured in the perforations of the pipe and their outer ends secured in the perforations of the casing, said pipes being extended forwardly and in the direction of the usual travel of the automo-

bile, and an exhaust pipe leading to and extended into the casing.

2. In combination with an exhaust pipe, of a casing having a flanged end through which is extended a second casing mounted in said casing, a pipe mounted in the second casing, branch pipes connecting the pipe and second casing, said pipes being inclined toward the flanged end of the casing, a mixing chamber into which the exhaust empties, 25 a conoid deflector mounted in advance of the mixing chamber, whereby the exhaust gases are broken up before entering the mixing chamber.

In testimony whereof I affix my signature, 30 in the presence of two witnesses.

SAM W. FORNEY.
